No. 836,199.

PATENTED NOV. 20, 1906.

C. W. MORRIS.
PINTLE RETAINER.
APPLICATION FILED AUG. 8, 1905.

UNITED STATES PATENT OFFICE.

CHARLES WESTLEY MORRIS, OF NEWARK, NEW JERSEY

PINTLE-RETAINER.

No. 886,199.

Specification of Letters Patent.

Patented Nov. 20, 1906.

Application filed August 8, 1905. Serial No. 273,313.

To all whom it may concern:

Be it known that I, CHARLES WESTLEY MORRIS, a citizen of the United States, residing at Newark, in the county of Essex and 5 State of New Jersey, have invented a new and useful Improvement in Pintle-Retainers, of which the following is a specification.

This invention relates to pintle-retaining means whereby the pintle of a caster can be 10 securely held in various sizes of tubular posts, the invention relating especially to retaining means for use with casters used in connection with metal beds.

With this object in view the invention 15 comprises certain details of construction and peculiar combination and arrangement of parts as will be fully set forth in the following specification, and pointed out in the claim, reference being had to the drawings, in 20 which—

Figure 1 is a perspective view showing my improvement attached to the hollow post of a bed, the latter being partly broken away. Fig. 2 is a vertical sectional view of the same. 25 Fig. 3 is a perspective view of the upper bearing-plate, and Fig. 4 a perspective view of the lower bearing-plate between which the ball are held and which forms a support for the post of the bed. Fig. 5 is a detail plan 30 view of the retainer, showing it in position upon the pintle. Fig. 6 is a detail section drawn on the line 6-6 of Fig. 2. Fig. 7 is a detail view of the blank of one of the arms of the pintle-retainer by which the caster is connected to the bed-posts; and Fig. 8 is a detail 35 view of portions of two arms, showing the way they are connected.

In carrying out my invention I employ a yoke A, which is stamped from a single piece 40 of stout metal and comprising the vertical arms A' and the top horizontal connected member A². In the lower ends of the arms is held a shaft B, upon which is mounted a ball-bearing caster-roller C, the hub C' of which is 45 made of metal, and the periphery or tread C² of hard rubber or other material which will not rust, and to hold the tread upon the hub and prevent its slipping I provide the hub with a peripheral rib C³, which fits a socket 50 formed in the inner surface of the periphery or tread.

The hub C' of the roller has its sides concaved or recessed to receive antifriction-balls, which are held in place by disks C⁴, held upon 55 the shaft and which bear against the balls

and the arms of the yoke; as clearly illustrated in Fig. 2 of the drawings. When the roller is connected to the yoke, the balls and disks are first arranged in position and the roller inserted between the arms of the yoke. 60 The shaft is then passed through the said arms and roller, after which the ends are headed, which securely lock all the parts in position.

To the horizontal portion of the yoke is 65 connected a pintle D, which projects vertically therefrom, and fitting upon the pintle and resting against the horizontal member of the yoke is a ball-bearing supporting member E, upon which rests the lower end of the 70 bed-post F. The supporting member comprises a lower plate E', which is preferably stamped from a single piece of metal and has an annular semispherical-shaped groove E², which provides a raceway in which are held 75 antifriction-balls G, and the upper plate E³ of the support is also stamped from a single piece of metal and has a groove E⁴, similar to the groove E² of the plate E', and the edge of the plate E³ overlaps the extreme edge of the 80 plate E', which completely houses the balls and prevents the ingress of dust and dirt.

To provide an arrangement by which the 85 caster may be connected to various size tubular bed-posts and also to hold the sections of the supporting member together, I employ a pintle-retainer H, which is constructed of two flat spring-arms H', each arm being stamped from a single piece of metal in the blank form shown in Fig. 7 of the drawings, and the center portion of each arm is somewhat enlarged 90 and provided with a central opening H².

The pintle-retainer, as before stated, is formed of two arms H', which are riveted together at their center portions, so that they 95 will extend at right angles from each other in the form of a cross, and when thus arranged each arm is bent downwardly from the center and their extreme ends bent inwardly to provide foot portions H³, which engage the upper plate of the supporting member and hold the sections together. A pin I passes 100 through one of a series of apertures D' in the pintle and is engaged by the central portion of the pintle-retainer or arms of the same, 105 which securely holds the pintle-retainer in place.

From the foregoing it will be seen that when the caster is assembled, as shown in Figs. 1 and 2 of the drawings, the pintle-re- 110

tainer serves the double purpose of holding the plates of the supporting member together and also as means for connecting the pintle to the post of the bed, and it will be further seen that by pressing the upper end of the pintle-retainer down upon the pintle the arms H' will be bent or bowed outwardly and held in such position by inserting the pin through one of the openings in the end of the pintle, and thus adjusting the pintle-retainers to snugly fit various sizes of bed-posts.

From the foregoing it will be seen that I provide an exceedingly cheap, simple, and highly efficient device that is capable of ready and easy attachment, and when in position will be securely and permanently held against displacement, it being understood that it is only necessary in connecting the caster to a bed-post to insert the upper end of the pintle-retainer in the lower end of the post, and then by allowing the weight of the

bed to rest thereon the pintle will be readily pushed and locked in position.

In practice I propose to recess the ends of the foot portions of the arms of the pintle-retainer to snugly fit the pintle, as shown in Fig. 6 of the drawings, which will prevent any lateral movement or displacement of the lower ends of the arms.

Having thus fully described my invention, what I claim as new, and desire to secure by Letters Patent, is—

A device of the kind described comprising a caster-pintle having perforations in vertical alignment, of spring-arms slidably held on said pintle, and a pin adapted to fit in the perforations of the pintle, and limit vertical movement of the arms on the pintle.

CHARLES. WESTLEY MORRIS.
